EYE GLASS FRAME

Avis Jean Coval, Dayton, Ohio, assignor to The Univis
Lens Company, Dayton, Ohio, a corporation of Ohio

Application June 13, 1957, Serial No. 46,586

Term of patent 14 years

(Cl. D57—1)

Fig. 1 is a front perspective view of an eyeglass frame, showing my new design;

Fig. 2 is a front elevational view thereof;

Fig. 3 is a side elevational view thereof;

Fig. 4 is a cross-sectional view thereof taken on the line 4—4 of Fig. 2; and

Fig. 5 is a cross-sectional view thereof taken on the line 5—5 of Fig. 3.

The dominant features of my design reside in the portions shown in full lines on the drawing.

I claim:

The ornamental design for an eye glass frame, substantially as shown and described.
